United States Patent Office

Des. 187,848
Patented May 3, 1960

187,848

FAUCET HANDLE

Edward Hulyk, Cincinnati, Ohio, assignor to American Radiator & Standard Sanitary Corporation, New York, N.Y., a corporation of Delaware

Application December 23, 1959, Serial No. 58,779

Term of patent 14 years

(Cl. D91—3)

Fig. 1

Fig. 2

Figure 1 is a side elevational view of a faucet handle showing my new design.

Figure 2 is a top plan view thereof.

I claim:

The ornamental design for a faucet handle, substantially as shown.
